Application June 10, 1953, Serial No. 25,429

Term of patent 3½ years

(Cl. D74—1)

To all whom it may concern:

Be it known that we, Karl Domberger and Sol Rael, both citizens of the United States, and residents, respectively, of Maspeth, New York, and Jackson Heights, New York, have invented a new, original, and ornamental Design for a Letter-Opener or Similar Article, of which the following is a specification, reference being had to the accompanying drawing, forming a part hereof, in which:

Figure 1 is a perspective view of a letter-opener or similar article showing our new design, the hidden sides and end of the handle presenting a similar appearance to the side and end shown; and

We claim:

The ornamental design for a letter-opener or similar article, as shown and described.

KARL DOMBERGER.
SOL RUEL.
